**CROSSBOW CORRECTION DEVICE,
MOLTEN METAL PLATING FACILITY, AND
CROSSBOW CORRECTION METHOD**

TECHNICAL FIELD

The present invention relates to a crossbow correction device for correcting crossbow of a steel strip, a molten metal plating facility including the crossbow correction device, and a crossbow correction method for correcting crossbow of a steel strip.

BACKGROUND ART

In a facility for producing a steel strip, a steel strip wound around multiple rolls travels continuously, and various treatment is performed on the continuous steel strip. The steel strip wound around multiple rolls deforms (warps) in the strip width direction due to contact with the rolls and tension, etc. Therefore, such a facility has a crossbow correction device for correcting the shape (crossbow) of the steel strip in the strip width direction.

For instance, in a molten metal plating facility immersing a steel strip in a molten metal for plating, a crossbow correction device is provided in the vicinity of a wiping nozzle for removing excess molten metal adhering to the surface of the steel strip. With this configuration, since a gas is sprayed by the wiping nozzle to the steel strip which has been leveled by the crossbow correction device, the gas is uniformly sprayed to the steel strip, and a metal plating layer is formed with uniform thickness.

The crossbow correction device is used for correcting the shape (crossbow) of a steel strip in the strip width direction by using magnetic force and includes a plurality of electromagnets arranged in the strip width direction of the steel strip and facing each other so as to sandwich the steel strip (see Patent Document 1, for instance).

The magnetic force of the electromagnets acts on portions of the steel strip facing the electromagnets and sucks (levels) the portions of the steel strip. That is, by the plurality of electromagnets arranged in the strip width direction of the steel strip, respective portions of the steel strip facing the electromagnets are sucked, and thereby crossbow of the steel strip is corrected as a whole. Here, a force to correct the shape of the steel strip by each electromagnet is proportional to the magnetic force of each electromagnet, i.e., the current value supplied to each electromagnet.

CITATION LIST

Patent Literature

Patent Document 1: JP5632596B

SUMMARY

Problems to be Solved

However, since the magnetic force of each electromagnet is controlled based on a distance sensor so that the steel strip is positioned at a central position or at a predetermined position in the vicinity of the center between opposite electromagnets, load applied to a part of the electromagnets arranged in the strip width direction of the steel strip (magnetic force generated in the part of electromagnets; current value applied to the part of electromagnets) may increase in accordance with the shape of the steel strip or

2

pass line. Further, if the load applied to the part of electromagnets reaches maximum magnetic force which the electromagnets can generate, a problem arises in that crossbow of the steel plate cannot be corrected appropriately.

5 The present invention was made in view of the above problem, and an object thereof is to efficiently correct crossbow of a steel strip by electromagnets.

Solution to the Problems

To solve the above problem, a crossbow correction device according to the present invention for correcting crossbow of a steel strip by a magnetic force during conveyance comprises: a plurality of electromagnets arranged in a strip width direction of the steel strip and facing each other so as to sandwich the steel strip in a strip thickness direction; a moving mechanism capable of moving the electromagnets relative to the steel strip; and a controller configured to operate the moving mechanism, based on a current value flowing through the electromagnets.

To solve the above problem, a crossbow correction method according to the present invention for correcting crossbow of a steel strip by a magnetic force during conveyance comprises: arranging a plurality of electromagnets in a strip width direction while the plurality of electromagnets face each other so as to sandwich the steel strip in a strip thickness direction, and moving the electromagnets relative to the steel strip, based on a current value flowing through the electromagnets.

Advantageous Effects

With the crossbow correction device according to the present invention, it is possible to efficiently correct crossbow of a steel strip by electromagnets.

With the crossbow correction method according to the present invention, it is possible to efficiently correct crossbow of a steel strip by electromagnets.

BRIEF DESCRIPTION OF DRAWINGS

FIG. 1 is an explanatory diagram showing a structure of a molten metal plating facility according to the first embodiment.

FIG. 2 is an explanatory diagram showing a structure of a crossbow correction device in a molten metal plating facility according to the first embodiment.

FIG. 3 is an explanatory diagram showing a structure of a crossbow correction device in a molten metal plating facility according to the first embodiment.

FIG. 4 is a block diagram showing operation control of correcting crossbow in a molten metal plating facility according to the first embodiment.

FIG. 5A is an explanatory diagram showing operation of correcting crossbow in a molten metal plating facility according to the first embodiment.

FIG. 5B is an explanatory diagram showing operation of correcting crossbow in a molten metal plating facility according to the first embodiment.

FIG. 5C is an explanatory diagram showing operation of correcting crossbow in a molten metal plating facility according to the first embodiment.

FIG. 5D is an explanatory diagram showing operation of correcting crossbow in a molten metal plating facility according to the first embodiment.

FIG. 6A is an explanatory diagram showing a positional relationship between a steel strip and electromagnets in operation of correcting crossbow in a molten metal plating facility according to the first embodiment.

FIG. 6B is an explanatory diagram showing a relative positional relationship between a steel strip and electromagnets in operation of correcting crossbow in a molten metal plating facility according to the first embodiment.

FIG. 7 is an explanatory diagram showing a relationship of the suction forces of electromagnets in operation of correcting crossbow in a molten metal plating facility according to the first embodiment.

DETAILED DESCRIPTION

Embodiments of the crossbow correction device according to the present invention will now be described in detail with reference to the accompanying drawings. In the embodiments described below, the crossbow correction device according to the present invention is adopted in a molten metal plating facility. It will, of course, be understood that the present invention is not limited to the following embodiments. For instance, the crossbow correction device according to the present invention may be adopted in other facilities for producing a steel strip, and various modifications can be made without departing from the spirit of the present invention.

First Embodiment

With reference to FIGS. 1 to 4, the configuration of the molten metal plating facility including the crossbow correction device according to the first embodiment of the present invention will be described.

As shown in FIG. 1, the molten metal plating facility 1 includes a plating bath 11 storing molten metal M. A steel strip S fed to the molten metal plating facility 1 travels through the plating bath 11 (molten metal M), so that the molten metal M adheres to the surface of the steel strip S.

In the plating bath 11, a sink roll 12 and a plurality of (two in FIG. 1) in-bath rolls 13, 14 rotatably supported are provided. The sink roll 12 is one of multiple rolls around which the steel strip S is wound, and the steel strip S is continuously fed by the multiple rolls, including the sink roll 12. The traveling direction of the steel strip S traveling through the plating bath 11 (molten metal M) is changed by the sink roll 12 so that the steel strip S travels upward in the substantially vertical direction (toward the upper side in FIG. 1).

The in-bath rolls 13, 14 are disposed downstream of the sink roll 12 in the strip feeding direction (above the sink roll 12 in the vertical direction; on the upper side in FIG. 1) so as to sandwich the steel strip S, i.e., so as to face a first surface (on the left side in FIG. 1) and a second surface (on the right side in FIG. 1) of the steel strip S respectively.

The in-bath rolls 13, 14 are mechanically connected to roll moving motors 21, 22 capable of moving and bring the in-bath rolls 13, 14 close to the steel strip S, respectively. In the molten metal plating facility 1, by moving the in-bath rolls 13, 14 by driving the roll moving motors 21, 22, it is possible to bring the in-bath rolls 13, 14 into contact with the

steel strip S, and adjust the shape of the steel strip S in the strip width direction and the pass line of the steel strip S (feeding position).

A wiping nozzle 15 is disposed downstream of the in-bath rolls 13, 14 in the strip feeding direction (above the in-bath rolls 13, 14 in the vertical direction; on the upper side in FIG. 1) and adjusts the thickness of a metal plating layer formed on the surface of the steel strip S. The wiping nozzle 15 is mainly composed of a first nozzle unit 31 and a second nozzle unit 32 disposed so as to sandwich the steel strip S therebetween. The first nozzle unit 31 is disposed so as to face the first surface of the steel strip S, and the second nozzle unit 32 is disposed so as to face the second surface of the steel strip S.

The first nozzle unit 31 and the second nozzle unit 32 spray a predetermined gas to the steel strip S and thereby remove excess molten metal M adhering to the surface of the steel strip S. The thickness of the metal plating layer formed on the surface of the steel strip S in the molten metal plating facility 1 is adjusted by the distance of the steel strip S from the first nozzle unit 31 and the second nozzle unit 32 and the pressure of the gas sprayed to the steel strip S by the first nozzle unit 31 and the second nozzle unit 32.

A crossbow correction device 16 is disposed downstream of the wiping nozzle 15 in the strip feeding direction (above the wiping nozzle 15 in the vertical direction; on the upper side in FIG. 1) to correct the shape of the steel strip S. The crossbow correction device 16 is mainly composed of a first correction unit 41 and a second correction unit 42 disposed so as to sandwich the steel strip S therebetween. The first correction unit 41 is disposed (on a first side in the strip thickness direction of the steel strip S) so as to face the first surface of the steel strip S, and the second correction unit 42 is disposed (on a second side in the strip thickness direction of the steel strip S) so as to face the second surface of the steel strip S.

The first correction unit 41 and the second correction unit 42 apply magnetic forces to the steel strip S to correct the shape of the steel strip S in the strip width direction (crossbow correction, leveling) and suppress vibration of the steel strip S (damping).

As shown in FIGS. 2 and 3, the first correction unit 41 is provided with a support frame (first support member) 51 facing the steel strip S and extending in the strip width direction (horizontal direction; right-left direction in FIG. 2) of the steel strip S. The support frame 51 is mechanically connected to a first frame moving motor 52, a second frame moving motor 53, and a third frame moving motor 54 capable of moving the support frame 51 relative to a structure not depicted, in a plane (horizontal plane) perpendicular to the feeding direction of the steel strip S.

As shown in FIG. 3, the first frame moving motor 52 is connected to a first end (right end in FIG. 3) of the support frame 51 and moves the support frame 51 in the strip width direction (right-left direction in FIG. 3) of the steel strip S. The second frame moving motor 53 is connected to the first end of the support frame 51 and moves the first end of the support frame 51 in the strip thickness direction (up-down direction in FIG. 3) of the steel strip S. The third frame moving motor 54 is connected to a second end (left end in FIG. 3) of the support frame 51 and moves the second end of the support frame 51 in the strip thickness direction of the steel strip S.

For instance, when the second frame moving motor 53 and the third frame moving motor 54 are driven in the same direction, the support frame 51 is translationally moved (shifted) in the strip thickness direction of the steel strip S in

a plane (horizontal plane) perpendicular to the feeding direction of the steel strip; and when one of the second frame moving motor **53** or the third frame moving motor **54** is driven, or when the second frame moving motor **53** and the third frame moving motor **54** are driven in opposite directions, the support frame **51** is rotationally moved (skewed) in a plane (horizontal plane) perpendicular to the feeding direction of the steel strip.

As shown in FIG. 2, the support frame **51** has a plurality of (four in FIG. 2) moving blocks **55a**, **55b**, **55c**, **55d** arranged in the longitudinal direction of the support frame **51** (strip width direction of the steel strip **S**; right-left direction in FIG. 2) and extending below the support frame **51** (downward in the vertical direction). The plurality of moving blocks **55a** to **55d** are mechanically connected to a plurality of (four in FIG. 2) block moving motors **56a**, **56b**, **56c**, **56d** capable of moving the moving blocks **55a** to **55d** relative to the support frame **51** in the longitudinal direction, respectively.

Each of the block moving motors **56a** to **56d** is connected to the corresponding moving block **55a** to **55d** via a gear mechanism (not shown) accommodated in the support frame **51**. The moving blocks **55a** to **55d** are independently moved in the longitudinal direction of the support frame **51** by driving of the block moving motors **56a** to **56d**.

Of course, the present invention is not limited to the configuration including the plurality of block moving motors **56a** to **56d** which independently move the plurality of moving blocks **55a** to **55d** respectively, as in the present embodiment. For instance, the plurality of moving blocks **55a** to **55d** may be mechanically connected to one block moving motor (not shown) via a gear mechanism (not shown) accommodated in the support frame **51**, and the moving blocks **55a** to **55d** may be symmetrically moved in the longitudinal direction of the support frame **51** by driving of the one block moving motor.

Each of the moving blocks **55a** to **55d** has an electromagnet **57a**, **57b**, **57c**, **57d** applying a magnetic force to the steel strip **S**, and a distance sensor **58a**, **58b**, **58c**, **58d** for detecting a distance to the steel strip **S** (distance between the steel strip **S** and the electromagnet **57a** to **57d**). The electromagnet **57a** to **57d** and the distance sensor **58a** to **58d** are arranged in the longitudinal direction of each moving block **55a** to **55d** (vertical direction; up-down direction in FIG. 2). The electromagnet **57a** to **57d** is disposed upstream of the distance sensor **58a** to **58d** in the strip feeding direction (on the side closer to the first nozzle unit **31**; on the lower side in FIG. 2).

Further, as shown in FIG. 2, the support frame **51** is coupled with the first nozzle unit **31** via connection frames **51a** disposed on both ends (both right and left ends in FIG. 2).

Thus, when the support frame **51** is moved in the horizontal plane by driving of the first frame moving motor **52**, the second frame moving motor **53**, and the third frame moving motor **54**, the first nozzle unit **31** is moved in the horizontal plane in accordance with movement of the support frame **51** (see FIGS. 2 and 3). In addition, provision of a mechanism (not shown) for moving the first nozzle unit **31** relative to the support frame **51** enables accurate positioning of the first nozzle unit **31**.

As shown in FIGS. 2 and 3, the second correction unit **42** has a support frame (second support member) **61**, moving blocks **65a**, **65b**, **65c**, **65d**, electromagnets **67a**, **67b**, **67c**, **67d**, and distance sensors **68a**, **68b**, **68c**, **68d**, like the first correction unit **41**.

The support frame **61** of the second correction unit **42** is mechanically connected to a first frame moving motor **62**, a second frame moving motor **63**, and a third frame moving motor **64**, and the first frame moving motor **62**, the second frame moving motor **63**, and the third frame moving motor **64** are configured to move the support frame **61** in a plane (horizontal plane) perpendicular to the feeding direction of the steel strip **S**, like the support frame **51** of the first correction unit **41**.

Further, the support frame **61** is coupled with the second nozzle unit **32** via connection frames **61a** disposed on both ends (both right and left ends in FIG. 2). Thus, when the support frame **61** is moved in the horizontal plane by driving of the first frame moving motor **62**, the second frame moving motor **63**, and the third frame moving motor **64**, the second nozzle unit **32** is moved in the horizontal plane in accordance with movement of the support frame **61**. In addition, provision of a mechanism (not shown) for moving the second nozzle unit **32** relative to the support frame **61** enables accurate positioning of the second nozzle unit **32**.

The moving blocks **65a** to **65d** of the second correction unit **42** are mechanically connected to block moving motors **66a**, **66b**, **66c**, **66d** respectively, and are independently moved in the longitudinal direction of the support frame **61** (strip width direction of the steel strip **S**), like the moving blocks **55a** to **55d** of the first correction unit **41**.

In the present embodiment, the support frames **51**, **61**, the first frame moving motors **52**, **62**, the second frame moving motors **53**, **63**, the third frame moving motors **54**, **64**, moving blocks **55a** to **55d**, **65a** to **65d**, and the block moving motors **56a** to **56d**, **66a** to **66d** form a moving mechanism capable of moving the electromagnets **57a** to **57d**, **67a** to **67d** relative to the steel strip **S**. The first frame moving motor **52**, **62**, the second frame moving motor **53**, **63**, and the third frame moving motor **54**, **64** can move the support frames **51**, **61** in a plane perpendicular to the feeding direction of the steel strip **S**, and the block moving motors **56a** to **56d**, **66a** to **66d** can move the electromagnets **57a** to **57d**, **67a** to **67d** in the strip width direction of the steel strip **S**.

As shown in FIGS. 2 and 3, the crossbow correction device **16** is provided with edge sensors **59**, **69** for detecting the position of ends of the steel strip **S** in the strip width direction. One edge sensor **59** is disposed on a first end (left end in FIG. 3) of the support frame **51** of the first correction unit **41**. This edge sensor **59** detects a first end (left end in FIG. 3) of the steel strip **S** in the strip width direction. The other edge sensor **69** is disposed on a second end (right end in FIG. 3) of the support frame **61** of the second correction unit **42**. This edge sensor **69** detects a second end (right end in FIG. 3) of the steel strip **S** in the strip width direction. That is, two edge sensors **59**, **69** disposed on the first correction unit **41** and the second correction unit **42** detect both ends of the steel strip **S** in the strip width direction.

Of course, the present invention is not limited to the configuration including the edge sensors **59**, **69**, one on each support frame **51**, **61** as in the present embodiment. For instance, both the edge sensor **59** for detecting a first end of the steel strip **S** in the strip width direction and the edge sensor **69** for detecting a second end of the steel strip **S** in the strip width direction may be disposed on one of the support frame **51** or the support frame **61**, or may be disposed on each of the support frame **51** and the support frame **61**.

Further, as shown in FIG. 4, the molten metal plating facility **1** includes a controller **17** for operation control of correcting crossbow of the steel strip **S**. The controller **17** is

electrically connected to roll moving motors 21, 22 and to the crossbow correction device 16.

More specifically, information such as current values flowing through the electromagnets 57a to 57d, 67a to 67d of the crossbow correction device 16, detection results (distances between the steel strip S and the moving blocks 55a to 55d, 65a to 65d) by the distance sensors 58a to 58d, 68a to 68d, and detection results by the edge sensors 59, 69 are send to the controller 17. On the basis of the information, the controller 17 controls driving of each of the roll moving motors 21, 22, the first frame moving motors 52, 62, the second frame moving motors 53, 63, the third frame moving motors 54, 64, and the block moving motors 56a to 56d, 66a to 66d.

The value of current flowing (supplied) to each electromagnet 57a to 57d, 67a to 67d is obtained by the controller 17 which controls operation of the electromagnet 57a to 57d, 67a to 67d. Of course, the present invention is not limited to the present embodiment. For instance, an ammeter for detecting the value of current supplied to each electromagnet may be provided.

With reference to FIGS. 1 to 7, the operation of the molten metal plating facility including the crossbow correction device according to the first embodiment of the present invention will be described.

In the plating process by the molten metal plating facility 1, the steel strip S is continuously fed by the multiple rolls (including the sink roll 12) and is immersed in the molten metal M in the plating bath 11. Thereby, the molten metal M adheres to the surface thereof (see FIG. 1).

Then, the steel strip S travels upward in the vertical direction via the sink roll 12 and the in-bath rolls 13, 14, and upon passing between the first nozzle unit 31 and the second nozzle unit 32, excess molten metal M adhering to the surface is removed.

At this time, crossbow of the steel strip S is corrected and vibration of the steel strip S is damped by the crossbow correction device 16 disposed downstream of the wiping nozzle 15 in the strip feeding direction. The operation of correcting crossbow in the molten metal plating facility 1, including the first step to fourth step shown below, is controlled by the controller 17 (see FIG. 4).

First, in the first step (second movement control), the controller 17 drives the plurality of block moving motors 56a to 56d, 66a to 66d to move the plurality of moving blocks 55a to 55d, 65a to 65d into predetermined positions, based on detection results of the edge sensors 59, 69 in a state where current is not applied to the electromagnets 57a to 57d, 67a to 67d (see FIGS. 2 to 4).

In the first step, the plurality of moving blocks 55a to 55d, 65a to 65d (electromagnets 57a to 57d, 67a to 67d and distance sensors 58a to 58d, 68a to 68d) are individually moved in the longitudinal direction of the support frames 51, 61 (strip width direction of the steel strip S), and respective two moving blocks 55a, 55d, 65a, 65d positioned on the outer side in the strip width direction of the steel strip S are disposed in the vicinity of the ends of the steel strip S in the strip width direction, and respective two moving blocks 55b, 55c, 65b, 65c positioned on the inner side in the strip width direction of the steel strip S are disposed so that the moving blocks 55a to 55d, 65a to 65d are spaced substantially equally (see FIGS. 5A and 5B).

With the first step, since magnetic forces generated by the plurality of electromagnets 57a to 57d, 67a to 67d arranged in the strip width direction efficiently act across the steel strip S in the strip width direction, in the present embodiment, it is possible to sufficiently level the steel strip S

without using electromagnets 57a to 57d, 67a to 67d having a large suction force. Of course, in case of using electromagnets 57a to 57d, 67a to 67d having a sufficiently large suction force, the first step may be eliminated from the operation of correcting crossbow.

In a case where the steel strip S does not exist in a range of motion of the moving blocks 55a to 55d, 65a to 65d in the support frames 51, 61, the controller 17 drives the first frame moving motors 52, 62 to move the support frames 51, 61, based on detection results of the edge sensors 59, 69.

Accordingly, the steel strip S is caused to exist in the range of motion of the moving blocks 55a to 55d, 65a to 65d in the support frames 51, 61, and the first step can be performed.

Next, in the second step (third movement control), the controller 17 drives the second frame moving motors 53, 63 and the third frame moving motors 54, 64 to move the support frames 51, 61 into predetermined positions, based on detection results of the distance sensors 58a to 58d, 68a to 68d in a state where current is not applied to the electromagnets 57a to 57d, 67a to 67d (see FIGS. 2 to 4).

At this time, the controller 17 computes a target shape (target pass line L₁) of the steel strip S, based on the shape 25 of the steel strip S (detection results of the edge sensors 59, 69 and distance sensors 58a to 58d, 68a to 68d (see FIG. 5C).

In the second step, the support frames 51, 61 (first correction unit 41, second correction unit 42, first nozzle unit 31, and second nozzle unit 32) are moved in the horizontal plane (in the strip thickness direction of the steel strip S) and positioned at a predetermined distance from the target pass line L₁ (see FIG. 5D). That is, the support frames 51, 61 (electromagnets 57a to 57d, 67a to 67d) are positioned parallel to the pass line (target pass line L₁) of the steel strip S in a range where the suction forces of the electromagnets 57a to 57d, 67a to 67d sufficiently can act on the steel strip S.

With the second step, since the variation in position of the electromagnets 57a to 57d, 67a to 67d relative to the steel strip S is reduced (see FIG. 6A), in the present embodiment, it is possible to sufficiently level the steel strip S without using electromagnets 57a to 57d, 67a to 67d having a large suction force. Of course, in case of using electromagnets 57a to 57d, 67a to 67d having a sufficiently large suction force, the second step may be eliminated from the operation of correcting crossbow. Here, FIG. 6A shows the positional state of the steel strip S with respect to the target pass line L₁ between the first correction unit 41 and the second correction unit 42, where the long dashed double-dotted line shows the steel strip S before the second step (after the first step), and the solid line shows the steel strip S after the second step.

Next, in the third step (magnetic force control), the controller 17 operates the electromagnets 57a to 57d, 67a to 67d to correct crossbow of the steel strip S, based on detection results of the distance sensors 58a to 58d, 68a to 68d (see FIGS. 2 to 4 and 5E).

In the third step, current in accordance with the distance between the steel strip S and each electromagnet 57a to 57d, 67a to 67d is supplied to the electromagnet 57a to 57d, 67a to 67d, and suction force in accordance with (proportional to) the current value supplied to the electromagnet 57a to 57d, 67a to 67d acts on the steel strip S. More specifically, the suction force (magnetic force) of each electromagnet 57a to 57d, 67a to 67d, i.e., current value supplied to each

electromagnet 57a to 57d, 67a to 67d is adjusted so that the shape of the steel strip S coincides with (approximates to) the target pass line L₁.

With the third step, it is possible to appropriately correct crossbow of the steel strip (see FIG. 6B). Here, FIG. 6B shows the positional state of the steel strip S with respect to the target pass line L₁ between the first correction unit 41 and the second correction unit 42, where the long dashed double-dotted line shows the steel strip S before the third step (after the second step), and the solid line shows the steel strip S after the third step.

In the present embodiment, by adjusting the magnetic force of each electromagnet 57a to 57d, 67a to 67d, the steel strip S is positioned into the target pass line L₁, i.e., the central position between the electromagnets 57a to 57d and the electromagnets 67a to 67d which face each other (strictly, the central position between the distance sensors 58a to 58d and the distance sensors 68a to 68d).

Of course, the present invention is not limited to the present embodiment. For instance, the magnetic force of each electromagnet 57a to 57d, 67a to 67d may be adjusted in consideration of a relative positional relationship between the wiping nozzle 15 and the crossbow correction device 16, i.e., a relative positional relationship between the first and second nozzle units 31, 32 and the first and second correction units (electromagnets 57a to 57d and electromagnets 67a to 67d). More specifically, by adjusting the magnetic force of each electromagnet 57a to 57d, 67a to 67d so that the steel strip S is positioned into predetermined positions away from the central position between the electromagnets 57a to 57d and the electromagnets 67a to 67d which face each other, it is possible to reliably place the steel strip S into the central position between the first nozzle unit 31 and the second nozzle unit 32.

Further, the magnetic force of each electromagnet 57a to 57d, 67a to 67d may be adjusted in consideration of the thickness of the metal plating layer formed on the surface of the steel strip S. More specifically, by adjusting the magnetic force of each electromagnet 57a to 57d, 67a to 67d so that the steel strip S is positioned into predetermined positions away from the central position between the electromagnets 57a to 57d and the electromagnets 67a to 67d which face each other toward a side on which a thin metal plating layer is formed (e.g., a side adjacent to the electromagnets 57a to 57d), it is possible to vary the thickness of the metal plating layer formed on the surface of the steel strip S between the first surface and the second surface (front and back surfaces).

Next, in the fourth step (first movement control), the controller 17 drives the second frame moving motors 53, 63 and the third frame moving motors 54, 64 to move the support frames 51, 61, i.e., a group of the electromagnets 57a to 57d and a group of the electromagnets 67a to 67d, based on the current value supplied to each electromagnet 57a to 57d, 67a to 67d in a state where current is applied to the electromagnets 57a to 57d, 67a to 67d (see FIGS. 2 to 4).

At this time, the controller 17 performs a shift control of causing translational movement of the support frames 51, 61 in a predetermined condition and a skew control of causing rotational movement of the support frames 51, 61 in a predetermined condition (see FIGS. 5E and 5F).

The shift control in the fourth step includes determining a total current value ($I_{SUM1}=I_{57a}+I_{57b}+I_{57c}+I_{57d}$) supplied to the electromagnets 57a to 57d in the first correction unit 41 and a total current value ($I_{SUM2}=I_{67a}+I_{67b}+I_{67c}+I_{67d}$) supplied to the electromagnets 67a to 67d in the second cor-

rection unit 42, and causing translational movement of the support frames 51, 61 so as to reduce a difference between these total current values ($I_{SUM1}-I_{SUM2}\approx 0$, i.e., $I_{SUM1}\approx I_{SUM2}$). I_{57a} to I_{57d} and I_{67a} to I_{67d} represent a current value supplied to each electromagnet 57a to 57d, 67a to 67d.

The skew control in the fourth step includes determining the sum ($I_{SUM3}=I_{57a}+I_{57b}+I_{67c}+I_{67d}$) of a total current value (I_{57a}+I_{57b}) supplied to two electromagnets 57a, 57b positioned on a first side of the center in the strip width direction of the first correction unit 41 and a total current value (I_{67c}+I_{67d}) supplied to two electromagnets 67c, 67d positioned on a second side of the center in the strip width direction of the second correction unit 42, and the sum ($I_{SUM4}=I_{57c}+I_{57d}+I_{67a}+I_{67b}$) of a total current value (I_{67a}+I_{67b}) supplied to two electromagnets 67a, 67b positioned on the first side of the center in the strip width direction of the second correction unit 42 and a total current value (I_{57c}+I_{57d}) supplied to two electromagnets 57c, 57d positioned on the second side of the center in the strip width direction of the first correction unit 41, and causing rotational movement of the support frames 51, 61 so as to reduce a difference between these sums ($I_{SUM3}-I_{SUM4}\approx 0$, i.e., $I_{SUM3}\approx I_{SUM4}$).

In other words, the skew control in the fourth step includes imparting rotational movement to the support frames 51, 61 so as to minimize the difference between the sum ($I_{SUM3}=I_{57a}+I_{57b}+I_{67c}+I_{67d}$) of total current values supplied to the electromagnets 57a, 57b and the electromagnets 67c, 67d, which generate tension to rotate the support frames 51, 61 in one direction (counterclockwise in FIG. 5E, for instance) around the longitudinal center of the support frames 51, 61, and the sum ($I_{SUM4}=I_{57c}+I_{57d}+I_{67a}+I_{67b}$) of total current values supplied to the electromagnets 57c, 57d and the electromagnets 67a, 67b, which generate tension to rotate the support frames 51, 61 in the other direction (clockwise in FIG. 5E, for instance) around the longitudinal center of the support frames 51, 61.

In the fourth step, by combining the shift control and the skew control, the support frames 51, 61 (first correction unit 41, second correction unit 42, first nozzle unit 31, and second nozzle unit 32) are moved in the horizontal plane so that the electromagnets 57a to 57d, 67a to 67d have substantially the same (uniform) load (suction force), and thereby the steel strip S is moved from the aforementioned target pass line L₁ into a new pass line L₂ (see FIGS. 5E and 5F).

Of course, the present invention is not limited to the configuration in which the steel strip S is finally moved into a new pass line L₂ by moving the support frames 51, 61 while monitoring the current values I_{57a} to I_{57d}, I_{67a} to I_{67d} flowing through the electromagnets 57a to 57d, 67a to 67d, as in the present embodiment. For instance, a relationship between the change of current values I_{57a} to I_{57d}, I_{67a} to I_{67d} flowing through the electromagnets 57a to 57d, 67a to 67d and the displacement amount of the pass line (feeding position) of the steel strip S may be formulated or stored as data in advance; a new target pass line L₂ for equalizing the loads (suction forces) of the electromagnets 57a to 57d, 67a to 67d may be computed in advance (after the third step) based on the current values I_{57a} to I_{57d}, I_{67a} to I_{67d} flowing through the electromagnets 57a to 57d, 67a to 67d at a certain time point; and the support frames 51, 61 may be moved into positions at a predetermined distance from the computed target pass line L₂.

With the fourth step, it is possible to equalize and reduce the suction forces of the electromagnets 57a to 57d, 67a to 67d, i.e., the current values supplied to the electromagnets 57a to 57d, 67a to 67d (see FIG. 7). Here, FIG. 7 shows the

suction force of each electromagnet $57a$ to $57d$, $67a$ to $67d$ (in FIG. 7, "a" represents $57a$, $67a$, "b" represents $57b$, $67b$, "c" represents $57c$, $67c$, and "d" represents $57d$, $67d$) disposed in the strip width direction of the steel strip S, where the long dashed double-dotted line shows the suction force of each electromagnet $57a$ to $57d$, $67a$ to $67d$ before the fourth step (after the third step), and the solid line shows the suction force of each electromagnet $57a$ to $57d$, $67a$ to $67d$ after the fourth step.

In the fourth step, while performing the shift control and the skew control, the controller 17 adjusts the magnetic force of each electromagnet $57a$ to $57d$, $67a$ to $67d$ based on detection results of the distance sensors $68a$, $68b$, $68c$, $68d$ and controls the steel strip S so as to be placed at a predetermined position between the electromagnets $57a$ to $57d$ and the electromagnets $67a$ to $67d$ which face each other, and the current values I_{57a} to I_{57d} , I_{67a} to I_{67d} supplied to the electromagnets $57a$ to $57d$, $67a$ to $67d$ change in accordance with movement (translational movement and rotational movement) of the support frames 51, 61.

Accordingly, the first nozzle unit 31 and the second nozzle unit 32 are moved together with the support frames 51, 61 while keeping a predetermined distance from the steel strip S. Thus, it is possible to appropriately remove excess molten metal M adhering to the surface of the steel strip S by the first nozzle unit 31 and the second nozzle unit 32, and to form the metal plating layer with a desired thickness, without changing the distance of the first nozzle unit 31 and the second nozzle unit 32 from the steel strip S (see FIGS. 2 to 4).

In the present embodiment, by adjusting the magnetic force of each electromagnet $57a$ to $57d$, $67a$ to $67d$, the steel strip S is positioned into the target pass line L_1 (see the fourth step), i.e., the central position between the electromagnets $57a$ to $57d$ and the electromagnets $67a$ to $67d$ which face each other (strictly, the central position between the distance sensors $58a$ to $58d$ and the distance sensors $68a$ to $68d$).

Of course, the present invention is not limited to the present embodiment. For instance, the magnetic force of each electromagnet $57a$ to $57d$, $67a$ to $67d$ may be adjusted in consideration of a relative positional relationship between the wiping nozzle 15 and the crossbow correction device 16, i.e., a relative positional relationship between the first and second nozzle units 31, 32 and the first and second correction units (electromagnets $57a$ to $57d$ and electromagnets $67a$ to $67d$) or the thickness of the metal plating layer formed on the surface of the steel strip S.

The crossbow correction method according to the present invention is not limited to the operation of the crossbow correction device 16 described above and may include a fifth step (roll movement control) of moving the roll disposed upstream of the electromagnets in the strip feeding direction, based on the current value flowing through the electromagnets. That is, the operation of correcting crossbow in the molten metal plating facility 1 may include, in addition to the first step to the fourth step, the following fifth step.

In the fifth step (roll movement control), the controller 17 drives the roll moving motors 21, 22 to move the in-bath rolls 13, 14, based on the current values supplied to the electromagnets $57a$ to $57d$, $67a$ to $67d$ in a state where current is applied to the electromagnets $57a$ to $57d$, $67a$ to $67d$ (see FIG. 2).

In the fifth step, the in-bath rolls 13, 14 is moved toward and away from the steel strip S by driving of the roll moving

motors 21, 22 and positioned so as to further reduce the equalized load (suction force) of each electromagnet $57a$ to $57d$, $67a$ to $67d$.

With the fifth step, since the load (suction force) of each electromagnet $57a$ to $57d$, $67a$ to $67d$ substantially equalized in the first step to fourth step is further reduced, it is possible to more efficiently correct crossbow of the steel strip by the electromagnets $57a$ to $57d$, $67a$ to $67d$.

In the fifth step, while controlling the operation of the in-bath rolls 13, 14 and the roll moving motors 21, 22, the controller 17 adjusts the magnetic force of each electromagnet $57a$ to $57d$, $67a$ to $67d$ based on detection results of the distance sensors $68a$, $68b$, $68c$, $68d$ and controls the steel strip S so as to be placed at a predetermined position between the electromagnets $57a$ to $57d$ and the electromagnets $67a$ to $67d$ which face each other, and the current values supplied to the electromagnets $57a$ to $57d$, $67a$ to $67d$ change in accordance with movement of the in-bath rolls 13, 14.

Accordingly, the first nozzle unit 31 and the second nozzle unit 32 are moved together with the support frames 51, 61 while keeping a predetermined distance from the steel strip S. Thus, it is possible to appropriately remove excess molten metal M adhering to the surface of the steel strip S by the first nozzle unit 31 and the second nozzle unit 32, and to form the metal plating layer with a desired thickness, without changing the distance of the first nozzle unit 31 and the second nozzle unit 32 from the steel strip S (see FIGS. 2 to 4).

Of course, the present invention is not limited to the configuration in which the steel strip S is finally moved into a new pass line by moving the in-bath rolls 13, 14 while monitoring the current values flowing through the electromagnets $57a$ to $57d$, $67a$ to $67d$, as described above. For instance, a new target pass line for equalizing the loads (suction forces) of the electromagnets $57a$ to $57d$, $67a$ to $67d$ may be computed in advance (after the fourth step), and the in-bath rolls 13, 14 may be moved so that the steel strip S coincides with the computed target pass line.

The functions and effects of the present embodiment described above will be compared with prior arts, in conjunction with the characteristics of steel strips.

Generally, a steel strip fed continuously in a facility for producing a steel strip has a characteristic of moving (translating or rotating) in the strip thickness direction with the change of the type of steel and operational conditions, and with the operation of correcting crossbow.

In the prior arts, the translating or rotating steel strip is leveled by the magnetic force of an electromagnet, i.e., crossbow is corrected while movement of the steel strip is restricted by the magnetic force of an electromagnet. Thus, the electromagnet requires not only correction force of correcting crossbow of the steel strip but also restriction force of restricting movement of the steel strip. Therefore, a large load, i.e., current value, is applied to the electromagnet.

By contrast, in the present embodiment, since the electromagnet $57a$ to $57d$, $67a$ to $67d$ is (translationally or rotationally) moved based on the current value flowing through the electromagnet $57a$ to $57d$, $67a$ to $67d$, it is possible to observe movement of the steel strip S based on the current value flowing through the electromagnet $57a$ to $57d$, $67a$ to $67d$, and it is possible to move the electromagnet $57a$ to $57d$, $67a$ to $67d$ in accordance with movement of the steel strip S. That is, crossbow is corrected while movement of the steel strip S is allowed. Thus, the electromagnet $57a$ to $57d$, $67a$ to $67d$ requires only correction force of correcting crossbow of the steel strip S and does not require

13

restriction force of restricting movement of the steel strip S. Therefore, it is possible to reduce the load, i.e., current value applied to the electromagnet 57a to 57d, 67a to 67d.

In the prior arts, since crossbow is corrected while movement of the steel strip is restricted, the steel strip is conveyed in a constant position (pass line) relative to the molten metal plating facility (ground). By contrast, in the present embodiment, since crossbow is corrected while movement of the steel strip S is allowed, the steel strip S is conveyed while moving relative to the molten metal plating facility 1 10 (ground), i.e., while the pass line is changed.

REFERENCE SIGNS LIST

1 Molten metal plating facility	15	a mover extending along an entire width of the steel strip and configured to move the electromagnets relative to the steel strip; and
11 Plating bath		a controller configured to operate the mover, based on a current value flowing through the electromagnets, wherein the mover includes a first support member sup-
12 Sink roll		porting an electromagnet disposed on a first side in the strip thickness direction of the steel strip and a second support member supporting an electromagnet disposed on a second side in the strip thickness direction of the steel strip among the plurality of electromagnets, and the first support member and the second support mem-

64 Third frame moving motor of second correction unit (Moving mechanism)	55	
65a to 65d Moving block of second correction unit (Moving mechanism)		
66a to 66d Block moving motor of second correction unit (Moving mechanism)		
67a to 67d Electromagnet of second correction unit	60	
68a to 68d Distance sensor of second correction unit (Distance detector)		
69 Edge sensor of second correction unit	65	
The invention claimed is:		
1. A crossbow correction device for correcting crossbow of a steel strip by a magnetic force during conveyance, comprising:		
a plurality of electromagnets arranged in a strip width direction of the steel strip and facing each other so as to sandwich the steel strip in a strip thickness direction;		

15

4. The crossbow correction device according to claim 1, wherein the controller is configured to operate the mover, based on a detection result of a distance detector, in a state where current is not applied to the plurality of electromagnets.
5. A molten metal plating facility comprising:
a wiping nozzle for spraying a gas to a steel strip; and a crossbow correction device for correcting crossbow of the steel strip by a magnetic force during conveyance, wherein the crossbow correction device is the crossbow correction device according to claim 1, and wherein the wiping nozzle is configured to move together with the plurality of electromagnets in the strip thickness direction of the steel strip.
6. A crossbow correction method for correcting crossbow of a steel strip by a magnetic force during conveyance, comprising:
arranging a first plurality of electromagnets in a strip width direction on a first mover extending along an entire width of the steel strip on a first side of the steel strip in a strip thickness direction, and arranging a second plurality of electromagnets in the strip width direction on a second mover extending along the entire width of the steel strip on a second side of the strip in the thickness direction, while the first and second plurality of electromagnets face each other so as to sandwich the steel strip in a strip thickness direction, and
moving the first and second plurality of electromagnets relative to the steel strip in plane perpendicular to a feeding direction of the steel strip, based on a current value flowing through the first and second plurality of electromagnets,
wherein the moving step includes causing a rotational movement of the first mover as a unit and a rotational movement of the second mover as a unit, individually, the crossbow correction method further comprising:
a magnetic force control of adjusting respective magnetic forces of the first and second plurality of electromagnets, based on a distance between the steel strip and each of the first and second plurality of electromagnets; and
a first movement control of moving the first plurality of electromagnets and the second plurality of electromagnets,
wherein the first movement control includes causing the rotational movement of the first mover and causing the rotational movement of the second mover so as to reduce a difference between a first sum and a second sum, where the first sum is a sum of a total current value flowing through a part of the first plurality of

electromagnets positioned on a first side of a center in the strip width direction of the steel strip and a total current value following through a part of the second plurality of electromagnets positioned on a second side of the center in the strip width direction of the steel strip, and the second sum is a sum of a total current value flowing through the other part of the second plurality of electromagnets positioned on the first side of the center in the strip width direction of the steel strip and a total current value flowing through the other part of the first plurality of electromagnets positioned on the second side of the center in the strip width direction of the steel strip.

7. The crossbow correction method according to claim 6, wherein the first movement control includes causing translational movement of the first plurality of electromagnets disposed on the first side in the strip thickness direction of the steel strip and the second plurality of electromagnets disposed on the second side in the strip thickness direction of the steel strip so as to reduce a difference between a total current value flowing through the first plurality of electromagnets disposed on the first side in the strip thickness direction of the steel strip and a total current value flowing through the second plurality of electromagnets disposed on the second side in the strip thickness direction of the steel strip.

8. The crossbow correction method according to claim 6, further comprising:

a second movement control of moving each of the first and second plurality of electromagnets in the strip width direction of the steel strip, based on a position of an end of the steel strip in the strip width direction, in a state where current is not applied to the first and second plurality of electromagnets; and
a third movement control of moving each of the first and second plurality of electromagnets in the strip thickness direction of the steel strip, based on a distance between the steel strip and each of the first and second plurality of electromagnets, in a state where current is not applied to the plurality of first and second electromagnets.

9. The crossbow correction method according to claim 6, further comprising:

a roll movement control of moving a roll disposed upstream of the first and second plurality of electromagnets in the feeding direction of the steel strip based on the current value flowing through the first and second plurality of electromagnets.
